F. B. LA MAY

CAN OPENER

Filed June 24, 1924

FIG. 3

FIG. 4

FIG. 5

INVENTOR.
Frank B. La May
BY Osborne & Gurney
ATTORNEY

UNITED STATES PATENT OFFICE.

FRANK B. LA MAY, OF ROCHESTER, NEW YORK, ASSIGNOR TO LA MAY-SMITH-WALKER, INC., OF ROCHESTER, NEW YORK.

CAN OPENER.

Application filed June 24, 1924. Serial No. 722,010.

To all whom it may concern:

Be it known that I, FRANK B. LA MAY, a citizen of the United States, and a resident of Rochester, in the county of Monroe and State of New York, have invented a new and useful Improvement in Can Openers, of which the following is a specification.

The present invention relates to can openers of the type employing a rotary cutter operating in such manner as to sever an end from a can by cutting through the side wall in a plane adjacent and parallel to the end seam, an object of the invention being to provide a device of this character that is of simple, strong, and inexpensive construction, effective in its operation and not liable to get out of order.

Another object of the invention is to so support the cutter that it may be readily removed and cleaned without having to clean the entire device.

Another object of the invention is to provide a one piece frame which comprises a base and an overhanging arm forming a mounting for the operating mechanism and a housing for the cutter and gears.

A further object of the invention is by a novel frame construction to guard against any possible injury to a person operating or otherwise handling the device.

And, a still further object of the invention is to provide for a plurality of ways in which the frame member may be secured to a support.

To these and other ends the invention consists of certain parts and combinations of parts as will be fully set forth in the following description and particularly defined in the appended claims.

The accompanying drawings illustrating the invention are as follows:

Figure 1 is a top plan view of the can opener secured upon a support.

Fig. 2 is a side view of the device showing a can as supported when being opened.

Fig. 3 is a sectional detail on the line 3—3, Fig. 2.

Fig. 4 is a vertical sectional view through the cutter and parts carried on the cutter stud, the stud being shown in full.

And, Fig. 5 is a sectional detail on the line 5—5, Fig. 2, with the clamp removed.

Similar reference numerals refer to similar parts throughout the several views.

The operating mechanism is mounted upon a suitable supporting frame which, in this instance, comprises a plate having a return bend 1 intermediate its ends to form a base 2 and a forwardly and, preferably, slightly upwardly inclined arm 3. The base portion 2 may be secured upon a support 4 by means of screws 5, see Fig. 5, which engage through openings 6 in the base, or by means of a clamp 7 which carries an adjustable clamping screw 8 and is formed at its upper end with an inwardly turned arm 9 resting upon and removably secured to the base by a screw 10, the base 2 being recessed at 11 to receive the vertical portion of the clamp and hold it against turning when the apparatus is disconnected from a support. It will be observed that in the event the support 4 is not provided with an overhanging ledge so as to permit the use of the clamp, the latter may be removed and the base 2 secured to the support by the screws 5.

Rotatably mounted in the arm 3 adjacent the outer end thereof is a stud 12 to the upper end of which is secured the inner end of an operating crank 13, having a handle 14 at its outer end, while fixed to the inner end of the stud is a comparatively thin spur gear 15 and a knurled friction roller 16, the gear lying against the under face of the arm and the roller being formed with a reduced portion 17 whereby the knurled portion is spaced from the gear.

The gear 15 meshes with a similar gear 18 fixed to a stud 19 rotatably mounted in the arm 3 and in the short inner end 20 of a lever 21 which is pivotally mounted at 22 to swing in a plane parallel to the arm 3. Also fixed to this stud 19 is a cutter disc 23 spaced from the gear 18 by a collar 24 and having its cutting edge in a plane slightly below the friction roller 16. Swinging the lever 21 causes the cutter to be swung into or out of operative position, the stud moving through an archial slot 25 in the arm 3, and a latch 26 also pivoted at 22 in common with the lever 21 and movable across the outer face of the lever holds the stud 19 against axial movement, this

latch being formed at its free end with a slot 27 which engages the reduced portion 28 of the stud under the shoulder 29.

Operation of the device is as follows:—

5 The base 2 of the frame plate is rigidly secured to the support 4 either by means of the clamp 7 or screws 5, the latter being used in the event of the clamp not being employed. The cutter 23 is swung to inoperative position away from the friction roller 16 by movement of the lever 21. The can, indicated in dotted lines at 30, and having an end 31 to be severed, is placed in position as shown with the friction roller 16 10 engaging the inner face of the flange 32 of the can. The lever 21 is then swung to throw the cutter into operative position, that is with the centers 12, 19 and 22 in alignment, and in moving to such position 15 it cuts through the side wall of the can just under the end wall 31. The can is thus supported upon the cutter and held in place by the friction roller 16. It is also held at a slight angle from the vertical due to the 20 upward inclination of the supporting arm 3, the purpose of this being to reduce the overhang of the arm 3 to a minimum and yet have the can clear the support 4 and the clamp 7. Rotation of the operating crank 25 13 and the consequent rotation of the knurled friction roller 16 and cutter 23 causes the roller to act as a feed wheel and effect rotation of the can with the result that the end of the can is severed by the side 30 wall being cut in a plane just under such end. The operative of course holds one hand under the can while operating the 35 crank 13 with the other.

After opening a can the severed end is 40 removed from the opener by swinging the lever 21 to move the cutter to its inoperative position. The latch 26 by engaging the finger piece 33 thereon may then be disengaged from the stud 19 and the latter 45 with gear, collar and cutter removed, cleaned and replaced without having to clean the entire apparatus.

Aside from the removable feature of the cutter and the simplicity of construction of 50 the can opener, it will be observed that the cutter and gears are on the under side of the supporting arm 3 and that the latter acts as a housing and guard to prevent injury to the operative while opening a can or 55 otherwise handling the device.

What I claim is:

1. In a can opener, a lever pivoted intermediate its ends, a stud rotatably mounted in one arm of the lever, a disc cutter fixed 60 to said stud, and means for releasably holding the stud in said lever and against axial movement.

2. In a can opener, a support having a slot therethrough, a lever pivoted intermediate 65 its ends, a stud rotatably mounted in one

arm of the lever and movable in said slot on operation of the lever, a disc cutter fixed to said stud, and a pivoted latch slotted to receive a reduced portion of said stud and adapted to releasably hold the stud against 70 axial movement.

3. In a can opener, a support having a slot therethrough, a lever, and a latch movable over the face of the lever, both such members having a common pivotal connection to said support and intermediate the ends of the lever, a stud extending through said slot and rotatably mounted in one arm of said lever, and a cutter on said stud, said latch being slotted to engage a reduced portion of said stud and releasably hold the latter against axial movement.

4. In a can opener, a frame including a base having a recess in its outer edge, and a clamp comprising a vertical portion engaging in said recess, an adjustable clamping screw, and a lateral arm extending inwardly from said vertical portion and detachably secured upon the top of said base.

5. In a can opener, a frame formed of a plate having a return bend intermediate its ends to form a base and a supporting arm, means for securing the base to a support, and operating mechanism mounted upon said arm.

6. In a can opener, a frame formed of a plate having a return bend intermediate its ends to form a base and a supporting arm, means for securing the base to a support, and operating mechanism mounted upon 100 said arm being inclined upwardly for the purpose specified.

7. The combination, in a can opener, of a support having a slot therethrough, a stud rotatably mounted in the support, a gear 105 and a friction roller fixed to the stud in spaced relation and under the support, an operating crank fixed to said stud above the support, a lever pivoted intermediate its ends to the support, a second stud rotatably mounted in one arm of said lever and movable in said slot, a gear and a disc cutter fixed to said second named stud, both said gears intermeshing and the cutter lying below the plane of said friction roller, and means for releasably holding said second named stud against axial movement.

8. The combination, in a can opener, of a support comprising a plate having a return bend intermediate its ends to form a 120 base and a supporting arm, the latter having a slot therethrough, a stud rotatably mounted in the supporting arm, a gear and a friction roller fixed to said stud in spaced relation and under said arm, an operating crank fixed to said stud above said arm, a lever pivoted intermediate its ends to said arm, a second stud rotatably mounted in one arm of said lever and movable in said slot, a gear and a disc cutter fixed to said sec- 125 130

ond named stud, both said gears intermeshing and the cutter lying below the plane of said friction roller, and a pivoted latch mounted on the face of said lever and slotted to engage a reduced portion of said second named stud and releasably hold the latter against axial movement.

9. The combination, in a can opener, of two rotatably mounted studs, a driving connection between the two studs, an operating crank fixed to one of the studs, a lever pivoted intermediate its ends and in one arm of which one of said studs is mounted, a disc cutter fixed to such lever stud and a friction roller fixed to the other of said studs, said lever being operable to swing said cut-

ter into and out of operative position with respect to said friction roller.

10. The combination, in a can opener, of two rotatably mounted studs, a driving connection between the two studs, an operating crank fixed to one of the studs, a lever pivoted intermediate its ends and in one arm of which one of said studs is mounted, a disc cutter fixed to said lever stud and a friction roller fixed to the other of said studs, said lever being operable to swing said cutter into and out of operative position with respect to said friction roller, and means for releasably holding the lever stud in place.

FRANK B. LA MAY.
